C. A. HELDERMAN & J. S. RUSSELL.
SEMAPHORE POLE.
APPLICATION FILED MAR. 13, 1912.

1,029,442.

Patented June 11, 1912.

UNITED STATES PATENT OFFICE.

CHARLEY ALEXANDRIA HELDERMAN AND JOHN STEPHEN RUSSELL, OF GOLD HILL,
NORTH CAROLINA.

SEMAPHORE-POLE.

1,029,442.

Specification of Letters Patent.

Patented June 11, 1912.

Application filed March 13, 1912. Serial No. 683,592.

To all whom it may concern:

Be it known that we, CHARLEY A. HELDERMAN and JOHN S. RUSSELL, citizens of the United States, residing at Gold Hill, in the 5 county of Rowan and State of North Carolina, have invented certain new and useful Improvements in Semaphore-Poles, of which the following is a specification.

This invention relates to the subject of 10 signals, and has in view an improved semaphore pole attachment for use with oil-burning lamps, whereby the lamp may be easily raised to the top of the pole and there held in position, and lowered when it is desired 15 to light the same or clean it.

One of the objects of the invention is to provide a semaphore pole that has, in connection with a mechanism for raising and lowering a light, a device that will steady the 20 lamp while being placed on top of the pole, and further when the lamp has been put in its place to lock the operating means.

A further object of the invention is to provide means for securely holding the 25 lamp on top of the pole after it has been positioned by the raising and lowering mechanism, so as to prevent it from being blown or jarred off.

With these and other objects in view, 30 which will be readily apparent to those skilled in the art, the invention consists in the construction, combination and arrangement of parts hereinafter more particularly described, illustrated and claimed.

35 While susceptible of various minor changes, the invention is exemplified by the preferable form thereof shown in the accompanying drawings, in which—

Figure 1 is a perspective view of a semaphore pole showing the present device applied thereto. Fig. 2 is a perspective view 40 of the pole showing the mechanism for raising and lowering the lamp unlocked, and the lamp raised out of the guard member 45 ready for lowering. Fig. 3 is a detail perspective view of the raising and lowering mechanism.

Like references designate corresponding 50 parts in the several figures of the drawing.

The semaphore pole which may be of any 55 preferred construction, is designated in the accompanying drawing by the reference numeral 1, and has arranged around the top edge thereof a guard member 2, which is preferably made of spring wire or other

suitable material which will effectively and yieldingly hold a lamp inclosed thereby, and still permit none of the light given out by the lamp to be in any way obstructed. The 60 said guard extends around all sides of the pole so as to prevent movement in any lateral direction of a lamp that may be placed within it.

A guide member 3, preferably a length of 65 ordinary pipe, having a substantially inverted J shape upper portion, is secured to the pole by bearing eyes 4, which hold the pipe in such a manner that it may be rotated by means of a handle 5, which is secured at a position within reach of an operator on 70 the ground. The said guide pipe 3 is preferably formed in two sections which are connected by the coupling member 6, which because of its greater diameter, as compared with that of the guide pipe forms a bearing 75 support for the pipe, by resting upon one of the bearing eyes 4. Thus, it will be observed that the said guide pipe is rotatably supported, and because of the fact that the inverted J shaped portion is at right-angles 80 to the handle secured to the lower portion of the pipe, when the said handle is rotated in the arc of a circle it will bring the said J shaped portion out of its normal position over the top of the pole. The said guide 85 member 3 has within it a raising and lowering element, preferably in the form of a cable 7 that is long enough to permit the lamp to be raised to the top of the pole and conveniently lowered when desired. Attached to one end of the said cable is a lamp 90 8 preferably of the type shown in the accompanying drawing, and having a rounded head portion 9 that is designed to be engaged by a spring clamp 10, that is secured 95 on the downwardly extending portion of the inverted J shaped part of the pipe. When the lamp is at the upper part of the guide pipe the greater part of the cable 7 is at the bottom of the pipe and for convenience sake 100 may be wound around a cleat 11.

In order to prevent unauthorized parties from tampering with the signal lamp the handle 5 is locked to the pole 1 by a hasp 12 and padlock 13.

From the foregoing description it will be observed that when the lamp is desired to be removed from the top of the pole as shown in Fig. 1, the proper party may unlock the lock 13 and release the handle 5 so as to 110

permit of a free rotary movement of the 5 guide member 3. Then the rope 11 may be pulled sufficiently to release the lamp 8 from its resting place on the top of the pole, and 10 high enough so as to clear the guard member 2, when it may be turned to one side and lowered by allowing the slackening of the cable 7 through the lower end of the guide pipe. After the lamp has been lighted or 15 cleaned it is drawn upwardly by pulling on the cable 7 until the rounded head 9 of the lamp is firmly pressed into engagement with the spring clamp 10 on the downwardly extending portion of the inverted J shaped 20 part of the pipe. This is done to hold it steady so that it may be accurately placed over and into the guard clamp 2, when the 25 guide member 3 is rotated by the handle 5 to bring the lamp into position for lowering onto the top of the pole. When this position is reached the cable is slackened and the lamp allowed to seat itself in the guard member. The handle 5 may be then locked to the pole as previously described and the 30 rope wound upon the cleat 11 previously mentioned. The device is then ready for service, and from the foregoing description the many uses and advantages of the invention 35 will be readily apparent.

It will of course be understood, that the invention is to be used upon the ordinary semaphore pole in such a manner, that the 40 guard member will in no way affect or obstruct the working of the usual colored semaphore arms. These arms are not shown in the drawing for the reason that any well known forms thereof may be used in connection with the kind of lamp shown.

What we desire to claim by Letters Patent

is:—

1. The combination with a semaphore pole, of a guide member having a raising and lowering element for the lamp associated therewith, means for locking the guide member to the pole, and means on the pole for engaging the lamp.
2. The combination with a semaphore pole, of a lamp, a guide member, a raising

and lowering elements for the lamp associated with the guide member, means on the 50 guide member for steadyng the lamp when elevated, means for locking the device to the pole, and means on the pole for engaging the lamp.

3. The combination with a semaphore 55 pole, of a lamp having a head portion, a guide member, a raising and lowering element for the lamp, means on the guide member for engaging the head portion of the lamp, means for locking the guide member 60 to the pole, and means on the pole for yieldingly engaging the lamp.

4. The combination with a semaphore pole, of a lamp, a guide pipe rotatably secured to the pole, means on the pipe for engaging the lamp, means for locking the lamp to the pole, and raising and lowering means for the lamp associated with the pipe.

5. The combination with a semaphore 70 pole, of a lamp, a guide pipe rotatably secured to the pole, a spring clamp member for holding the lamp steady secured to the guide pipe, a lock for locking the guide pipe to the pole, retaining means on the pole for the lamp, and raising and lowering means 75 for the lamp associated with the pipe.

6. The combination with a semaphore pole of a lamp having a head portion, a guide pipe having an inverted J shaped upper section, a spring clamp member for 80 holding the lamp steady secured thereto, bearing eyes for rotatably supporting the said guide pipe, a handle projecting laterally from the pipe, a lock for locking the handle to the pole, a guard on the pole for 85 yieldingly engaging the lamp, and raising and lowering means for the lamp associated with the pipe.

In testimony whereof we hereunto affix our signatures in the presence of two witnesses.

CHARLEY ALEXANDRIA HELDERMAN.

JOHN STEPHEN RUSSELL.

Witnesses:

H. P. SMITH,

R. C. L. MANNEY.
